UNITED STATES PATENT OFFICE.

WINFIELD S. MORRIS, OF NEW YORK, N. Y.

SOFA AND CHAIR BED.

1,095,465.

Specification of Letters Patent.

Patented May 5, 1914.

Application filed June 22, 1911. Serial No. 634,798.

To all whom it may concern:

Be it known that I, WINFIELD S. MORRIS, a citizen of the United States, and a resident of New York city, in the county of New York and State of New York, have invented certain new and useful Improvements in Sofa and Chair Beds, of which the following is a specification.

The invention relates to improvements in sofa and chair beds and the like and consists in the novel features and combinations of parts hereinafter described, and particularly pointed out in the claims.

The object of the invention is to provide a novel and efficient sofa or chair-bed construction which may be made to produce a bed of adequate length and conveniently folded with the mattress in position on the spring or bed sections into the space afforded by the sofa or chair-frame to convert the article into a sofa or chair.

The structure embodying my invention comprises a sofa or chair frame and a bed frame capable of being folded within and concealed by the sofa or chair frame or extended therefrom to constitute a bed of adequate length. The bed portion of the article will preferably comprise a supporting frame detachable entirely, if desired, from the sofa or chair frame and four bed-sections, one being a head section which may be concealed within the back of the sofa or chair and the other three being hinged to one another in series and foldable within the sofa or chair frame and having the main spring for the mattress secured thereto.

The invention will be fully understood from the detailed description hereinafter presented, reference being had to the accompanying drawings, in which:

Figure 1 is a perspective view of a chair or sofa embodying the bed-construction of my invention, the bed-construction being shown as folded into the chair or sofa frame and the seat-cushion being, for clearness of illustration, omitted; Fig. 2 is a side elevation, partly broken away and partly in section, of a portion of the same, the bed-construction being illustrated in its outwardly extended position by solid lines and in a partly folded position by dotted lines; Fig. 3 is a perspective view showing the bed-construction complete and in its outwardly extended position to constitute a bed; Fig. 4 is a top view of the same, with the chair or sofa-frame in horizontal section on a line

slightly above the bed-frame members; Fig. 5 is a vertical longitudinal section of the same on the dotted line 5—5 of Fig. 4; and Fig. 6 is a substantially corresponding view, 60 with the bed construction shown as folded into the chair or sofa frame to the position illustrated in Fig. 1.

The article of furniture presented herein comprises two related main parts, to-wit: a chair or sofa frame and a foldable bed of novel construction adapted thereto and which may be withdrawn entirely therefrom when desired.

The chair or sofa frame comprises sides 70 or ends 10 and a cushioned back 11 which preferably inclines downwardly and forwardly and leaves a space behind the lower portion of the same, as shown in Figs. 5 and 6. The sides or ends 10 are shown as 75 solid and in their main part as of less height than the back 11, but these features of the construction may be varied at will, since it is commonly known that it is also usual to have the sides or ends 10 and back 11 of the 80 same height and also to have said sides or ends of open or bar construction in their upper portions. The general style of the chair or sofa frame will vary with the taste or inclination of the manufacturer. 85

The chair or sofa frame snugly receives between its sides or ends 10 the bed-frame and is equipped with certain features adapting it thereto, these being the vertical leaves 12 hinged to the front edges of said parts 10 90 and the downwardly and forwardly inclined bars 13 projecting laterally toward each other from the inner sides of the rear edges of said parts 10. When the bed-frame is folded within the chair or sofa frame, the leaves 12 95 will be turned to their transverse position shown in Fig. 1, in which position they afford a finish to the front of the article and conceal the vertical edges of the parts carried by the bed-frame, and when the bed-frame is to 100 be extended said leaves will be folded outwardly against the outer faces of the sides or ends 10, as shown in Figs. 3 and 4, so as to be out of the way of the bed-frame.

The bars 13 serve as tracks for a rear 105 hinged section 14 of the bed-frame and to turn and guide said section upwardly when the other portions of said frame are folded and the frame as a whole is pushed into the chair or sofa frame, as will be understood on 110 reference to Figs. 5 and 6. The front of the chair or sofa frame is also afforded a

finishing front rail 15, which may have a plain cabinet finish or be upholstered as may be desired and is carried by the bed-frame.

5 The chair or sofa frame may be made of wood, while the general bed-frame parts will preferably be made of metal.

10 The bed-frame or bed-member of the article of furniture comprises two rectangular side frames 16 affording top rails 17 and legs 18, the aforesaid rear or head bed-section 14 hinged to the rear legs 18 and three main bed-sections 19, 20, 21 hinged to one another in series (at 22, 23). The sections 19, 20, 21 will preferably be of iron and present an open frame to properly receive the spring 24 for the mattress 25. The hinged head section 14 will also be in the form of an open iron frame upon which a spring 26 will be secured to support a head mattress section 27, the latter by preference being fastened on said spring so as to remain in fixed relation thereto during the folding and unfolding of the bed. The mattress 25 will, also, preferably be fastened on the spring 24.

25 The head-section 14 is provided at its outer corners with rollers 28 to engage the aforesaid bars 13, and said section in the open position of the bed is held in an upwardly and rearwardly inclined position by 30 means of bars 29 pivotally secured at their upper ends thereto and at their lower ends carrying pivoted shoes 30 slidably held in vertical guides formed by the rear legs 18 and bars 31 secured at their lower ends thereto and at said ends serving as stops to arrest the shoes 30 and thereby enable the bars 29 to support the section 14 in its desired inclined position.

35 The bed-section 20 is pivotally mounted upon a transverse rod 32 extending between and connecting the front legs 18, and said section 20 is adapted when the bed is extended, to lie horizontally, as shown in Fig. 5, supported on said rod 32, and, when the bed is folded, to stand vertically within the confines of the frames 16, as shown in Fig. 6. The section 20 is formed with side bars or plates 33 preferably of triangular outline apertured at their apices to receive and form 40 bearings to engage the rod 32, and said bars or plates 33 support the side rails of the bed-section 20 suitably above the rod 32 when the device is in use as a bed and hold the same inwardly within the frames 16 when the bed-portions are folded and the device is to be used as a chair or sofa. The rod 32 is about in line with the vertical center of the section 20 when the latter is considered as in its horizontal position, and 45 hence when the section 20 is turned into its vertical position about one-half of the section extends below and the other half above the horizontal plane of the rod 32. The bars or plates 33 are connected by rods 34, 35 50 which stiffen and strengthen the section 20,

and the ends of the rod 35 extend beyond the bars or plates 33 and constitute stops to engage the lower notched ends of flat sleeves 36 secured to the frames 16 and arrest the section 20 in its horizontal position.

55 The bars or plates 33 have secured to them angle-bars 136 to which the front rail 15 is secured and whose position is varied in accordance with the position of the bed section 20, said front rail standing vertically, 75 as shown in Figs. 1 and 6 when the article is to be used as a chair or sofa and extending horizontally out of the way, as shown in Figs. 2 and 5, when the bed sections are extended for use as a bed.

80 The outer section 19 of the bed has side rails and an outer end rail and said side rails have secured to them angle plates 37 which when said section 19 is folded inwardly, as shown in Figs. 1 and 6, rest on the top-rails 17 of the side frames 16 and support said section 19 in a horizontal position. The outer end rail of the bed-section 19 is provided with foldable legs 38, of a character common in this art, for supporting the outer or foot end of the section 19 when the article is in use as a bed. The side bars or rails of the bed-section 19 at their inner ends extend below the front ends of the side bars or rails of the section 90 20, as shown in Fig. 5, and at such extending portions serve during the unfolding of the bed as levers for turning the section 20 to its horizontal position, as hereinafter explained. The bed-section 19, adjacent to its 100 connection with the middle section 20, has pivotally secured to its side rails a supplemental frame 39 comprising two short side bars, an outer end bar and a section of bed-spring 40. The frame 39 hangs idly downwardly when the bed is extended, as shown in Figs. 3 and 5, but when the bed is folded into the chair or sofa-frame said frame 39 lies horizontally along the front edge of what is then the seat and bridges the space 110 between the then upper ends of the plates 33 and the upper edge of the front rail 15, as shown in Fig. 6, and very much improves the durability and comfort of the chair or sofa seat, said frame 39 affording a rigid 115 support along the front edge portion of said seat for any cushion that may be placed thereon or any weight that might be imposed on such cushion. The inner bed-section 21 is hinged at its front edge, at 23, to the middle section 20 and at its rear edges, 120 rests upon, when horizontal, a rear transverse bar 41 extending between the rear legs 18, as shown in Fig. 5. In the folded condition of the bed the rear side edges of the bed-section 21 rest upon the downwardly and forwardly inclined guide-bars 42, as shown in Fig. 6, said bars 42 at their upper ends merging into the transverse bar 41.

125 The means provided at present for main-

taining the middle section 20 in a horizontal position when the bed is extended for use, are the pins 43 and hooks 44, said pins extending transversely of the top rails 17 of the frames 16 and said hooks preferably being concealed within flat sleeves 36 extending downwardly and forwardly from said top rails. The hooks 44 are of bar form and pivotally mounted upon the outer ends of the rod 35 connecting the plates 33 of the middle bed section 20, and hence said hooks have a movement with said section 20, said section when being turned to its horizontal position shown in Figs. 2 and 5, moving said hooks upwardly through the sleeves 36 to engage the pins 43 and drawing said hooks downwardly along said sleeves 36 when turned upwardly toward its vertical position. The hooks 44 may operate by gravity to engage the pins 43, but preferably I will provide within the sleeves 36 leaf springs 46 flexed against the hooks and normally pressing them in a direction toward the pins 43.

The pins 43 and hooks 44 hold the inner end of the middle section 20 in its upper or horizontal position and prevent the folding down of the bed members at the hinges 23 except when the hooks 44 are detached from the pins 43. As convenient means for withdrawing the hooks 44 from the pins 43 when it is desired to fold the bed sections within the chair or sofa frame, I provide flexible connections 47 of piano wire or other suitable material, secured to the bed section 19 and the hooks 44 and extending through the front legs 18, as shown in Fig. 2. When it is desired to fold the bed sections, the outer section 19 is first turned upwardly, as indicated by dotted lines in Fig. 2, and this movement of said section has the effect of drawing on the flexible connections 47 and thereby pulling the hooks 44 from the pins 43 or to the position indicated in Fig. 2 by dotted lines, and thereupon the inner end of the middle section 20 having been released, said section may turn downwardly and inwardly on the supporting rod 32. The fact that the inner end of the middle section 20 is, when the bed is extended, held in its horizontal position by the hooks 44 and pins 43, results in the adjoining end of the bed section 21 being firmly supported in its horizontal position, while at the same time the inner or rear end of said section 21 is supported on the transverse bar 41. When the bed section 20 is in its horizontal position, the end portions of the rod 35 pass into the notched lower ends of the sleeves 36 and cooperate therewith as stops to prevent the inner end of the bed member 20 from turning upwardly beyond its proper horizontal position and its front end from folding downwardly on the hinges 22, with the result that the inner end of the bed section 19 is also held in its horizontal position. The hooks 44 may be manually operated, if preferred, but I prefer to arrange for their automatic operation, in the manner described, or in any other manner which might be deemed desirable.

There are various connections known to me for operating the hooks 44 by a movement of the bed section 19, and hence I do not limit my invention to the employment of the piano wire flexible connections 47.

If we assume that the bed is in its extended position shown in Fig. 5, and it is desired to close the same, the attendant will raise the bed section 19 from its foot edge and fold the legs 28 against the end rail of said section, and thereupon said section 19 will be turned over inwardly between the side frames 16, which will support said section 19 by receiving upon their upper edges the angle plates 37 carried by said section, as shown in Figs. 1 and 6. The turning inwardly of the bed section 19 upon the side frames 16 results in the bed section 20 turning inwardly on the rod 32 to a vertical position between the side frames 16, and in the bed section 21 being drawn downwardly to an inclined position extending from the lower end of the then vertical bed member 20 to the guides 42, which in the folded condition of the bed support the inner end of the section 21, as shown in Fig. 6. The folding inwardly of the bed section 19 also results in the supplemental frame 39 being carried upwardly to a horizontal position at the then upper side of said section 19, while the turning inwardly and downwardly to a vertical position of the bed section 20 results in the foot rail 15 being turned outwardly to a vertical position, with its upper edge in line with the lower edge of the supplemental frame 39 and its lower edge in a recess 48 in a transverse bar 49 extending between the front legs 18 of the side frames 16. The bed sections 19, 20, 21 having thus been folded between the side frames 16, the latter, with the entire bed structure, is pushed inwardly between the sides 10 of the chair or sofa frame, and this has the effect of causing the rollers 28 carried by the head section 14 to ride upwardly on the inclined track bars 13 and in turning said section 14 into substantially a vertical position partly behind the back 11 of the chair or sofa, as shown in Fig. 6, the entire bed structure then being confined within the limits of the chair or sofa frame and said frame being completed across its lower front portion by the rail 15 and bar 49. After the bed structure has been entirely confined within the chair or sofa frame, the hinged leaves 12 will be turned from their position indicated in Fig. 4 to that shown in Fig. 1, thereby concealing the ends of the rail 15 and bar 49 and affording a proper finish to the article. Upon the up-

per or exposed section of the folded bed will, of course, be placed a suitable cushion or other covering enabling the article to be employed as a chair or sofa. The bed may 5 readily be opened for use, the closing- actions hereinbefore described occurring in the reverse order.

An important feature of my invention is that in the construction presented I am enabled to obtain a bed of full length and also 10 fold it within the confines permitted by a chair or sofa, and a further important accomplishment of my invention is that the mattress 25 may remain on the spring 24 15 during the folding of the bed and that a very commodious space, shown in Fig. 6, is left between the folded mattress to afford room to receive the pillows, bed coverings or the like. The middle bed section 20 is of 20 considerable length, and hence the mattress 25 is not sharply folded, but folded on a triangular outline, allowing adequate room between the folded portions for the bed covering and the like.

25 What I claim as my invention and desire to secure by Letters Patent, is:

1. A chair or sofa bed comprising a main exterior frame having sides and a back-member, and a movable foldable bed adapted 30 to be confined within said exterior frame or extended therefrom for use as a bed and comprising independent side supporting frames withdrawable from said main exterior frame, a head-section hinged to said 35 frames and adapted to be turned up into a substantially vertical position behind said back-member, three hinged-together mattress supporting sections the middle one of 40 which is pivotally mounted in said side frames so as to lie horizontally or stand vertically, means for maintaining said hinged-together sections in their open horizontal 45 position and means for supporting the outer two of said sections from said side frames when the bed is folded; substantially as set forth.

2. A chair or sofa bed comprising a main exterior frame having sides and a back-member, and a movable foldable bed adapted to 50 be confined within said exterior frame or extended therefrom for use as a bed and comprising side supporting frames, a head-section hinged to said frames and adapted to be turned upwardly behind said back-member, three hinged-together mattress supporting sections the middle one of 55 which is pivotally mounted in said side frames so as to lie horizontally or stand vertically, means for maintaining said 60 hinged-together sections in their open horizontal position and means for supporting the outer two of said sections from said side frames when the bed is folded, said head-section being equipped with means for supporting it in an upwardly inclined position

independently of said exterior frame, and said exterior frame having downwardly and forwardly inclined members for directing said head-section into a substantially vertical position behind said back-member when 70 the bed is pushed inwardly into said frame; substantially as set forth.

3. A chair or sofa bed comprising a main exterior frame having sides and a back-member, and a movable foldable bed adapted 75 to be confined within said exterior frame or extended therefrom for use as a bed and comprising side supporting frames, a head-section hinged to said frames and adapted to be turned upwardly behind said back-member, three hinged-together mattress supporting sections the middle one of which is pivotally mounted in said side-frames so as to lie horizontally or stand vertically, means for maintaining said hinged-together sections in their open horizontal position and means for supporting the outer two of said sections from said side frames when the bed is folded, said head-section being equipped 80 with means for supporting it in an upwardly inclined position independently of said exterior frame and provided at its outer corners with rollers, and said exterior frame having downwardly and forwardly inclined bars (13) to be engaged by said rollers and 85 for directing said head-section into a substantially vertical position behind said back-member when the bed is pushed inwardly into said frame; substantially as set forth.

4. A chair or sofa bed comprising a main exterior frame having sides and a back-member, and a movable foldable bed adapted 90 to be confined within said exterior frame or extended therefrom for use as a bed and comprising side supporting frames, a head-section hinged to said frames and adapted to be turned upwardly behind said back-member, three hinged-together mattress supporting sections the middle one of which is pivotally mounted in said side-frames so as to 95 lie horizontally or stand vertically, means for maintaining said hinged-together sections in their open horizontal position and means for supporting the outer two of said sections from said side frames when the bed is folded, said exterior frame having downwardly and forwardly inclined members for 100 directing said head-section into a substantially vertical position behind said back-member when the bed is pushed into said frame, combined with means for supporting said head-section in its operative position when the bed is extended comprising bars (29) pivoted to said head-section and carrying shoes (30) at their lower ends and bars 105 (31) secured to the said side-frames and therewith affording guides for said shoes and stops to arrest any undue descent thereof; substantially as set forth.

5. A chair or sofa bed comprising a main

- exterior frame having a back, sides and hinged vertical leaves at the front edges of said sides to be turned transversely for partly closing the opening between said sides 5 or outwardly to expose said opening, and a bed adapted to be confined within said exterior frame or extended therefrom and comprising foldable bed-sections a middle one of which is pivotally mounted to lie horizontally or stand vertically and the outer one of which has its side rails extended to pass below the side rails of said middle section, and a supplemental frame (39) carried by said outer section to lie 60 horizontally supported on the extension of its side rails when the bed is folded and extend along the front edge of what is then the seat-frame; substantially as set forth.
6. A chair or sofa bed comprising a main exterior frame having a back, sides and hinged vertical leaves at the front edges of said sides to be turned transversely for partly closing the opening between said sides or outwardly to expose said opening, and a front rail (15) for the chair or sofa carried by said middle section, whereby when the bed is extended said rail is turned downwardly and when said bed is folded said rail is moved 10 to its vertical position across the chair or sofa and may have its end edges concealed by said leaves; substantially as set forth.
7. An exterior chair or sofa frame or the like and a bed adapted to be confined therein or extended therefrom comprising foldable bed sections a middle one of which is pivotally mounted to lie horizontally or stand vertically, and a front rail (15) for the chair or sofa carried by said middle section, whereby when the bed is extended said rail is turned 15 downwardly and when said bed is folded said rail is moved to its vertical position across the front of said exterior frame and may have its end edges concealed by said leaves; substantially as set forth.
8. An exterior chair or sofa frame or the like and a bed adapted to be confined therein or extended therefrom comprising foldable bed sections a middle one of which is pivotally mounted to lie horizontally or stand vertically, and a front rail (15) for the chair or sofa carried by said middle section, whereby when the bed is extended said rail is turned 20 downwardly and when said bed is folded said rail is moved to its vertical position across the front of said exterior frame and may have its end edges concealed by said leaves; substantially as set forth.
9. An exterior chair or sofa frame or the like and a bed adapted to be confined therein or extended therefrom and comprising movable side frames, a foldable head-section secured to one end thereof, three hinged-together mattress supporting sections the middle one of which is pivotally mounted in said side-frames so as to lie 25 horizontally or stand vertically, means for maintaining said hinged-together sections in their open horizontal position and means for supporting the outer two of said sections from said side frames when the bed is folded, combined with vertical leaves hinged at the front edges of the sides of said exterior frame to be turned inwardly for 30 partly closing the opening between said sides or outwardly to expose said opening, and a front rail (15) for said exterior frame carried by said middle section, whereby when the bed is extended said rail is turned 35 downwardly and when said bed is folded said rail is moved to its vertical position across the front of said exterior frame and may have its end edges concealed by said leaves; substantially as set forth.
10. A chair or sofa bed comprising a main exterior frame having sides and a back-member, and a foldable bed adapted to be confined within said exterior frame and when folded afford a seat-member therefor and also 40 slideable outwardly between said sides, said bed comprising foldable mattress supporting sections and in addition a head section adapted to stand in a substantially vertical position behind said back-member when the article is in use as a sofa or chair and to lie in a substantially horizontal position when the article is in use as a bed.

Signed at New York city, in the county of New York, and State of New York, this 20th day of June A. D. 1911.

WINFIELD S. MORRIS.
